DISPENSING AND MEASURING APPARATUS

Filed June 2, 1928

Herbert C. Cushing
INVENTOR

BY *Victor J. Evans*

ATTORNEY

UNITED STATES PATENT OFFICE

HERBERT C. CUSHING, OF BABB, MONTANA

DISPENSING AND MEASURING APPARATUS

Application filed June 2, 1928. Serial No. 282,488.

This invention relates to certain novel improvements in dispensing and measuring apparatuses, and has for its principal object the provision of an improved construction of this character which will be highly efficient in use and economical in manufacture.

The device which forms the subject matter of my invention is adapted to be associated with hermetically sealed containers such as the cans employed for the dispensing of coffee and similar products.

An object of the invention, ancillary to the foregoing, is to arrange my device such that it will embody a piercing arrangement so as to facilitate the insertion thereof into a can.

Another object of the invention is to provide a device of the above named character which will embody a sealing ring so as to prevent the entrance of moisture into the can around my improved device.

Another object of the invention is to provide a device of the above named character which will be arranged such that it will measure a predetermined quantity of material to be dispensed therethrough.

A still further object of the invention is to arrange the device such that it will agitate the material in the can when it is desired to dispense the material therefrom.

Other objects will appear hereinafter.

The invention consists in the novel combination and arrangement of parts to be herein-after described and claimed.

The invention will be best understood by reference to the accompanying drawing, wherein a preferred form of construction is shown and in which:

Fig. 1 is an elevational view depicting a preferred embodiment of my invention in association with a container such as a coffee can;

Fig. 2 is an enlarged view, partly in elevation and partly in section, depicting my device in association with a container of the above named character;

Fig. 3 is a sectional view taken substantially on the line 3—3 on Figure 2;

Fig. 4 is a sectional view taken substantially on the line 4—4 on Figure 2;

Fig. 5 is a sectional view taken substantially on the line 5—5 on Figure 2; and

Fig. 6 is a sectional view taken substantially on the line 6—6 on Figure 2.

In the drawing, wherein a preferred embodiment of my invention is illustrated, 10 indicates a container of the type hereinbefore mentioned. 11 generically indicates my improved dispensing and measuring device. A dispensing and measuring device of the character I herein show is described and claimed in my co-pending application, Serial Number 232,113, filed on or about November 9, 1927, and entitled, Coffee meters.

My dispensing device includes a substantially rectangular portion 12 which is preferably elongated in length. In the wall 13 of this elongated portion 12, two spaced apart slots 14 and 15 are provided. Plates 16 and 17 are provided which are adapted to extend into the interior of the housing 12 through the slots 14 and 15 respectively. Mounted on the exterior surface of the wall 13 at substantially the midpoint between the slots 14 and 15, is a substantially U-shaped bearing member 18. A rock plate 19 is provided and has depending flanges 20 at the edges thereof which are adapted to be pivotally connected to the ears of the bearing member 18. A leaf spring 21 is provided which is disposed between the outer surface of the wall 13 and the inner side of the rock member 19 and serves to hold said rock member in a position such that the plate 17 will be held in a position such that it will tend to close passage through the member 12. When the plate 17 is disposed in this position, the plate 16 is arranged so as to have the inner edge thereof disposed to extend a slight distance interiorly of the housing 12, as is clearly illustrated in Figure 2.

The wall 22 of the housing 12, which is preferably disposed opposite the wall 13, is arranged so as to be elongated and is provided with a sharpened edge 23 so as to provide a piercing element. The walls 24 and 25 of the housing 12, extend below the inner end of the wall 13 and the inner ends thereto are rounded to provide sharpened

edges 26, said edges merging into the edges 23 of the wall 22 as shown in Fig. 4. Openings 27 are provided in the extended portions of the wall members 24 and 25, for a purpose to be made apparent presently. A flange member 28 is disposed around the housing 12 so as to be disposed at the lower end of the wall 13 and this flange member 28 includes an upwardly extending portion 29 that is extended along the wall 22. The flange member 28 is secured to the housing 12 in any approved manner so as to be rigidly connected thereto to prevent displacement thereof. Arranged on the side of the device provided with the boss 29 is a downwardly depending boss 30 which is preferably arranged so as to be disposed outwardly with respect to the wall 22 and a locking screw 31 is provided adjacent the outer end of this boss 30. A washer 32' of fibrous material is disposed below the flange member 28, and therefore, when the member 11 is arranged such that the piercing element 23 will be caused to cut a hole in the upper side of the can in order that the device may be arranged in the manner shown in Figure 2, this washer will prevent the passage of air into the can. When the device is arranged in the manner shown in Figure 2, the locking screw 31 is run in so as to engage the can and thus prevent displacement of the device 11.

It is apparent that the wall 13 is truncated and therefore, the portions disposed within the can will be opened toward this wall 13. Therefore, when the can is inverted as shown in Figure 2, the material therein will be caused to pass through the openings 27 and through this open side, and will flow down into the interior of the housing 12. The user of the device, by depressing the rocking member 19, may cause the plate 16 to be moved into closing position with respect to the interior of the housing 12, and at this same time, the plate 17 will be retracted from closing position. Therefore, the material which will have been disposed in the housing 12 between the area between the plates 16 and 17 will be dispensed therefrom and by regulating the size of this space, the amount of material dispensed may be controlled. It is apparent that this feature of the device affords a means for measuring the material which is obviously an advantage. As soon as the user releases the member 19, the spring 21 will re-position the parts in the position shown in Figure 2.

I have found that material such as coffee is sometimes slow pouring; that is, it tends to cake and does not freely flow through a dispenser such as I have indicated. I, therefore, provide an agitating means which comprises the following structure. Disposed interiorly of the housing 12, at the lower end of the wall 13 is a shaft member 32. An agitating member comprising arms 33 formed in the manner

best depicted in Figures 2 and 5 is provided and includes portions that are adapted to be wrapped around the shaft 32 as indicated at 34. Portions 35 extend beyond these wrapped around portions and extend through suitable openings 36 in the plate 16. Therefore, when the plate 16 is moved inwardly, it is apparent that the arms 33 will be pivoted about the shaft 32 and thus the material in the region of the open side of the device and the openings 27 will be agitated and it will therefore freely flow into the dispensing device. The open side referred to hereinbefore is indicated by 37 in Figure 6, wherein it will be seen that ample space is provided for the passage of the material into the interior of the housing 12.

It is apparent from the foregoing description that I have provided a device which will embody an arrangement such that it may be expeditiously inserted into a hermetically sealed can. Further, the device embodies an arrangement which will prevent air passage into the can when it is in installed position. In addition to the foregoing, the device embodies an arrangement which will be expeditiously installed, and which will be concealed from view and this arrangement is such that it will agitate the material so as to cause entrance thereof into the dispensing and measuring portion of the device.

While I have illustrated and described the preferred form of construction for carrying my invention into effect, this is capable of variation and modification, without departing from the spirit of the invention. I, therefore, do not wish to be limited to the precise details of construction herein set forth, but desire to avail myself of such variations and modifications as come within the scope of the appended claim.

Having thus described my invention, what I claim as new and desire to protect by Letters Patent is:

A dispensing and measuring device including a housing, one of the walls of said housing being provided with slots and having its inner end portion disposed in a plane below the inner end of the wall of the housing, opposite thereto, and said inner end portion being provided with sharpened edges, said housing having opposite corresponding walls extending downwardly and having rounded inner end portions provided with sharpened edges merging into the first mentioned sharpened edge, said opposite corresponding wall portions having openings formed therein, a stop shoulder formed on said housing, a pintle extending through said housing, agitating members pivotally mounted on said pintle and arranged for movement toward the inner end of said first mentioned wall portion, valve members extended through said slots, an extension on said agitating members and extended

through openings formed in one of said valve members, a means carried by the housing on the exterior thereof for alternately moving said valve members, and means for securing said housing to a container with the shoulder abutting and adjacent wall of said container.

5 In testimony whereof I affix my signature.
HERBERT C. CUSHING.
